UNITED STATES PATENT OFFICE.

WILLIAM F. LOHSE AND ELMER H. LOHSE, OF OMAHA, NEBRASKA.

EGG-TESTER.

1,330,199.

Specification of Letters Patent.

Patented Feb. 10, 1920.

Application filed August 8, 1919. Serial No. 316,063.

To all whom it may concern:

Be it known that we, WILLIAM F. LOHSE and ELMER H. LOHSE, citizens of the United States, residing at Omaha, in the county 5 of Douglas and State of Nebraska, have invented certain new and useful Improvements in Egg-Testers, of which the following is a specification.

This invention relates to an improvement 10 in an egg tester having a somewhat similar construction to that shown in U. S. Letters Patent No. 1,209,969, granted to William Humphery, dated Dec. 26, 1916, and subsequently assigned to applicants, and has for 15 its object to provide certain features relating to operation and simplicity of parts found to be of great advantage, and considered to be a material improvement as compared with the construction shown in said 20 Letters Patent.

In the accompanying drawing forming a part of the present application, Figure 1 is a front view of the device. Fig. 2 is a sectional view through the case and reflector 25 on line 2—2 of Fig. 1. Fig. 3 is a sectional view through the case and reflector on line 3—3 of Fig. 1; Fig. 4 is a view illustrating an electrical circuit. Fig. 5 is a view showing the inner side of the front wall of the 30 case. Fig. 6 is an enlarged detail showing an adjustable switch-member. Fig. 7 is a rear end view of the reflector on an enlarged scale. Fig. 8 is a sectional view on line 8—8 of Fig. 7.

Referring now to the drawing for a more particular description, numeral 5 indicates the case of a portable egg tester, said case preferably being constructed of material which is electrically non-conductive, and 40 provided with a lid 6, the front, upright wall *a* of the case below the lid, being provided with an opening 7. At 8 is indicated a door for said opening, and by means of a pair of spring-hinges 9 the door will normally remain closed, and will substantially 45 fill the opening. Upon the bottom of the case, adjacent to the door, are shown a pair of stops 10. Numerals 11 indicate flanges or projections provided for the lower part 50 of the door, and, as described, the door may be swung inwardly against the force of the springs *b* of the hinges 9, the stop-members 10, when engaged by said flanges, operating to limit the arc of movement of the door.

55 Numerals 12 indicate a pair of apertures provided for the door, and suitably secured

upon the door and projecting inwardly of the case is a reflector 13, this being substantially elliptical in cross-section, its divergent end opening upon the apertures 12. At 60 14 is indicated an electric light which is disposed within and secured to the collar *c* of the reflector, said light 14 being arranged in an electrical circuit, energized by any suitable means, the means herein shown being 65 electric batteries 15.

Mounted upon the front, upright wall *a* of the case, above the door 8, is an electrical contact-plate 16 provided with a binding-post 17. Numeral 18 indicates an angularly formed bracket which is secured to the upper part of the door, midway between the ends thereof, and having an upwardly projecting arm *d* disposed adjacent to the plate 16, and mounted on the arm *d* is an electrical contact-piece or switch-member 19, preferably having the form of a threaded pin.

The mounting of the threaded pin 19 upon the bracket is such that it may be adjusted longitudinally, nuts 20 (best shown 80 in Fig. 6) being threaded thereon at opposed sides of the arm *d* of said bracket; and electrically connected with the binding-post 17 is an electrical conductor 21 in communication with a battery 15. 85

At 22 is indicated an electrical conductor in communication with the electric light 14 and with one of the batteries 15, and at 23 is indicated a conductor in electrical communication with the electric light and with 90 the pin or switch-member 19.

The normal positions of parts are as shown in Fig. 2, the door being closed, and the pin or electrical contact-piece 19 being disposed closely adjacent to the plate 16, and therefore, normally, the electrical circuit will be 95 broken.

When in use, an operator manually places the eggs partly within the apertures 12, and thereby causes the door to swing inwardly 100 for engagement of the pin 19 with the plate 16, and thereby the electrical circuit will be established to cause the light to be reflected for inspection of the eggs, the springs *b* causing the door to become closed and causing 105 the electrical circuit to be broken when the eggs are removed.

The parts are so adjusted that a contact of the pin 19 with the plate 16 will be simultaneous with the engagement of the projections 11 with the stop-members 10, this being 110 of advantage since the door is rigid and

operates as a rock-lever, and the stop-members operate to prevent said member 19 from being pressed against the plate with undue force.

- 5 Numerals 24 indicate recesses which are formed in the wall of the reflector at the upper and lower sides thereof, and when the flanges 25 are secured to the door, these recesses provide draft apertures through
 10 which the air may move, to prevent undue heat within the reflector, and at 26 are indicated grooves which are provided for the reflector, said grooves being outwardly-divergent and formed in the parts of lesser curvature of the reflector and appearing above and below the lamp, each groove opening upon or terminating at a recess 24.
 It will be noted that when the reflector is secured to the door, the grooves 26 will be
 20 disposed in a plane midway between the egg-receiving apertures 12; and on account of this construction the light will be reflected to great advantage, the wall of the inwardly extending part of each groove near-
 25 est to an aperture 12, operating to reflect the light in a direction of said aperture and tending to focalize the rays of light nearer to the center of said aperture than ordinarily, so that any defects appearing in the
 30 eggs may be readily seen.

What we claim as our invention and desire to secure by Letters Patent is,—

1. An egg tester, comprising, in combination with a casing having an upright wall provided with an opening and an electrical contact-plate adjacent to said opening, a binding-post mounted on said electrical contact-plate, a door provided with apertures and mounted on the casing to permit swinging movements and disposed in said opening, a reflector provided with an electric light and mounted on the door, an electrical contact-piece movable with the door for engagement with said electrical contact-plate, and an electrical circuit including electrical conductors communicating with the binding-post, the electric light and said electrical contact-piece.

2. An egg tester, comprising, in combination with a casing having an upright wall provided with an opening and an electrical contact-plate adjacent to said opening, a binding-post mounted on the electrical contact-plate, a door disposed within said opening and provided with egg receiving apertures, said door having a hingeable mounting upon the casing to permit a swinging movement inwardly thereof, springs on said hinges to normally prevent a swinging movement of the door inwardly of the casing, a reflector provided with a lamp and

mounted on the door, an electrical contact-piece movable with the door for engagement with the electrical contact-plate, and an electrical circuit including electrical conductors communicating with the binding-post, the lamp, and said electrical contact-piece.

3. An egg tester comprising a casing having an upright wall provided with an opening and an electrical contact-plate adjacent to said opening, a binding-post mounted on the electrical contact-plate, a door disposed within said opening and provided with a flange and also provided with egg-receiving apertures, said door having a hingeable mounting at its upper end upon the casing to permit a swinging movement inwardly thereof, springs on said hinges to normally resist a swinging movement of the door inwardly of the casing, a reflector provided with a lamp and mounted on the door, an electrical contact-piece movable with the door for engagement with the electrical contact-plate, an electrical circuit including electrical conductors communicating with the binding-post, the lamp and said contact-piece, and a stop-member for limiting the arc of movement in one direction of the door, said stop-member being mounted upon the casing adjacent to the flange of said door.

4. In an egg tester, a casing having an opening in its side wall and provided with an electrical contact-plate, a binding-post mounted on the contact-plate, a door provided with a pair of apertures and disposed in said opening, hinges connecting the door with the casing to permit swinging movements of the door, a reflector open at one of its ends, said reflector being approximately of elliptical shape in cross-section and formed flaring toward its open end and provided with a pair of recesses opening upon opposed parts of its open end, and also provided with a pair of grooves formed divergent toward and opening upon said recesses, a lamp in the reflector midway between said grooves, an electrical contact-piece movable with the door for engagement with said electrical contact-plate, an electrical circuit including electrical conductors communicating with the binding-post, the lamp and said electrical contact-piece, and means normally tending to resist a movement of the door in one direction.

In testimony whereof, we have affixed our signatures in presence of two witnesses.
